Primary Examiner — Jack Reickel

CLAIM

The ornamental design for a display screen or portion thereof with animated graphical user interface for analyzing stock trends, as shown and described.

DESCRIPTION

The patent or application file contains at least one drawing executed in color. Copies of this patent or patent application publication with color drawing(s) will be provided by the Office upon request and payment of the necessary fee.

1. Display screen or portion thereof with animated graphical user interface for analyzing stock trends
